US00D968388S

(12) **United States Design Patent** (10) **Patent No.:** **US D968,388 S**
Andersson et al. (45) **Date of Patent:** **** Nov. 1, 2022**

(54) **COMPUTER**

(71) Applicant: **Siemens Aktiengesellschaft**, Munich (DE)

(72) Inventors: **Jan Andersson**, Erlangen (DE); **Stephan Hühne**, Wilhermsdorf (DE); **Andreas Morlock**, Pfintzal (DE); **Michael Rabinovich**, Nuremberg (DE); **Felix Weisenberger**, Lauterbourg (FR)

(73) Assignee: **Siemens Aktiengesellschaft**, Munich (DE)

(**) Term: **15 Years**

(21) Appl. No.: **29/677,022**

(22) Filed: **Jan. 16, 2019**

(30) **Foreign Application Priority Data**

Jul. 17, 2018 (EM) 005504834

(51) **LOC (13) Cl.** **14-02**

(52) **U.S. Cl.**

USPC **D14/314**; D14/301

(58) **Field of Classification Search**

USPC D14/172, 181, 301–302, 308, 314, 349,

D14/353, 356–359, 363, 432–434, 441,

D14/140.1–140.2, 204, 209.1, 203.8, 227,

D14/300, 313, 439; D10/122–132;

D23/351, 365–366, 393–394, 378;

D13/158–163, 177, 110, 164; D25/42

CPC G06F 1/1613; G06F 15/161; H05K 5/00;

H05K 5/04; H04R 1/02; G10K 13/00

See application file for complete search history.

(57) **CLAIM**

The ornamental design for a computer, as shown and described.

DESCRIPTION

FIG. 1 is a front view of a first embodiment of a computer, showing our new design;

FIG. 2 is a top view thereof;

FIG. 3 is a bottom view thereof;

FIG. 4 is a right side view thereof;

FIG. 5 is a left side view thereof; and,

FIG. 6 is a top, front and right side perspective view thereof. The broken lines in the drawings illustrate portions of the computer that form no part of the claimed design.

1 Claim, 6 Drawing Sheets
